UNITED STATES PATENT OFFICE

JOSEPH ANDRASSY, OF CLEVELAND, OHIO

LETTER BOX

Application filed October 5, 1927. Serial No. 224,141.

This invention relates to a letter box which is adapted to be supported on a wall or other supporting structure for receiving mail.

The main object of the invention is to provide a letter box of the character described which is simple in construction and comprises comparatively few parts and which is well adapted for quantity production at comparatively low cost.

10 Another object of the invention is to provide a letter box comprising a pair of telescoping sections and which may be locked in a closed position in order to prevent unauthorized persons from obtaining access thereto.

Another object of the invention is to provide a letter box of the character set forth which is provided with automatic means for opening the same so as to permit access there-

20 to by authorized persons.

Further and more limited objects of the invention will appear as the description proceeds and by reference to the accompanying drawings in which Fig. 1 is a view partly in front elevation and partly in section showing the box in the closed position and attached to a supporting structure; Fig. 2 is a view similar to Fig. 1 showing the box in the open position; Fig. 3 is a horizontal sectional view 25 on the line 3—3 of Fig. 1; Fig. 4 is a vertical sectional view showing the box in closed positions and mechanism for opening and closing the same; Fig. 5 is a vertical sectional view similar to Fig. 4 showing a box in the open position; and Fig. 6 is a vertical sectional view on the line 6—6 of Fig. 5.

Referring now to the drawings, the box comprises an outer casing 1 which is preferably made of sheet metal and which is provided on each side thereof with lateral tubular extensions or projections 2 and 3. The front of the casing 1 is provided with a rectangular opening 4 which is closed by a transparent plate 5 that is held in place by any suitable means. Also provided in the front of the casing 1 is an opening 6 in which is positioned a lock 7, the purpose of which will hereinafter appear. The bottom of the casing 1 is also provided with an opening 8 and secured to the bottom of the casing 1 is a

member 9 having a pair of oppositely disposed openings therein in which is slidably mounted a pin 10 having a U-shaped portion 11, as shown in Fig. 5 and which is held in the position shown in Fig. 5 by means of a coil spring 12, the purpose of which will hereinafter appear.

Fitting within the outer casing 1 is an inner casing 13 which is preferably rectangular in shape and the front of which is open for the greater part of its length. The top of the casing 13 is shaped as shown most clearly in Figs. 4 and 5 and is provided with a slot 14 normally closed by a cover 15 pivotally secured thereto as at 16. The inner casing 13 is provided at each side near the bottom thereof with projections 17 and 18 which project into the lateral extensions 2 and 3, respectively. Arranged within the tubular extensions 2 and 3, respectively, are a pair of coil springs 19 and 20 the lower ends of which are secured to the projections 17 and 18, respectively, and the upper ends of which are secured to pins 21 and 22 arranged within the upper end of the tubular extensions and extending therethrough.

Pivotal secured to the bottom of the inner casing 13 is a pawl or latch 23 which, when the inner casing 13 is in its lowermost position, enters and projects through the opening 8 in the bottom end of the outer casing 1. Arranged within the lower end of the outer casing 1 is a guide plate or deflecting member 24 which serves to direct or guide the pawl 23 into the opening 8. With the parts in the normal position the pawl 23 occupies the position shown in Fig. 4 and engages under the edge of the opening 8 and is held in this position by means of the pin 10 which is normally urged towards the left as shown in Fig. 4 by the coil spring 12.

With the parts in the position shown in Figs. 1 and 4, the coil springs 19 and 20 are under tension so that when the pin 10 is moved toward the right as seen in Fig. 4, the springs will move the inner casing to the position shown in Figs. 2 and 5. The front wall of the inner casing 13 is cut away to provide an opening 25 and secured to the upper edge of the opening 25 is a latch 26 which enters

100

an opening in the lock 7 and is engaged by the bolt of the lock. The inner casing 13 is also provided with an opening 28, which when the parts are in the normal position coincides with the opening 4 to enable one to view the interior of the box.

Secured to the bottom of the inner casing 13 is a flexible element 29 the opposite end of which is attached to the bottom end of the outer casing, as shown at 30. This flexible element 29 serves to limit the outward movement of the inner casing with respect to the outer casing. Pivotedly secured to the projecting ends of the pins 21 and 22 is a member 31 which is bent as shown in Figs. 1 and 2 which serves as a means for receiving packages or articles which are too large to be inserted into the letter box through the slot 14.

The outer casing 1 is secured to a support 32 in any suitable manner or the same may be secured to a wall or other convenient supporting structure, if desired. The parts normally occupy the position shown in Figs. 1 and 4 and in this position the openings 4 and 28 coincide so as to enable one to view the contents of the box for the purpose of ascertaining whether or not any mail has been received.

The box is of such a size that the usual size letter L will be retained in the upright position as shown in Figs. 1, 2, 4 and 5. The lock 7 is locked with a key in the usual manner and when locked prevents access to the interior of the box. When it is desired to open the box the lock 7 may be opened and the pin 10 is pushed inwardly toward the right as seen in Figs. 4 and 5 which movement releases the pawl or catch 23 and the springs 21 and 22 serve to elevate the inner casing to the position shown in Figs. 2 and 5, thus enabling letters, etc. to be removed through the opening in the front of the inner casing. The upward movement of the inner casing is limited by the flexible element 29.

A suitable name plate 33 may be secured to the front of the outer casing in any suitable manner for the purpose of enabling one to identify the letter box.

Various changes may be made in the details of construction without departing from the spirit of my invention and I wish my invention to be limited only in accordance with the scope of the appended claims.

It will now be clear that I have provided a letter box which accomplishes the objects of my invention as hereinbefore stated.

Having thus described my invention, what I claim is:

1. A letter box of the character set forth comprising a pair of telescoping casings, the outer casing having a longitudinally extending lateral projection at each side thereof defining a channel, the inner casing having an opening in its front wall and a pair of oppositely disposed projections adapted to enter said channels and work therein, spring

means arranged within said channels normally urging said casings apart, interlocking means on said casings for holding the same against relative movement, means for releasing said interlocking means whereby to permit said spring means to move said casings apart whereby to permit access to the interior thereof and a slot in said inner casing of sufficient size to permit a letter to be inserted therein.

2. A letter box of the character described comprising a pair of telescoping casings, the outer casing having a longitudinally extending projection at each side thereof defining a channel, the inner casing having a projection at each side thereof working in said channels respectively, a spring arranged within each of said channels and having its lower end attached to one of said projections and its upper end connected with said outer casing whereby to urge said casing apart, said outer casing having an opening in its bottom wall and a latch member carried by said inner casing and adapted to project through said opening and to engage the edge thereof to hold said casings against relative movement.

3. A letter box of the class described comprising an outer casing having an opening in its bottom, an inner casing fitting within said outer casing and slidable with respect thereto, said outer casing being provided at each side thereof with a channel and said inner casing having on each side thereof a projection adapted to project into and work within said channels, spring means arranged within said channels and connected with said inner and outer casings and tending to urge said casings apart, said inner casing having an opening in its front wall permitting access to the interior thereof when said casings are moved to a position to uncover said opening, latching means for holding said casings against relative movement, and means for releasing said latching means.

4. A letter box of the class described comprising a pair of telescoping casings substantially rectangular in cross section, the outer casing having an opening therein adjacent its bottom, the inner casing having a latch thereon adapted to project through said opening and to hold said casings against relative movement, said inner casing having a portion of its front wall cut away whereby to permit access to the interior thereof when said casings are moved apart a predetermined distance, said outer casing having lateral projections thereon at opposite sides thereof defining spring compartments, spring means arranged within said spring compartments and urging said casings apart, means for releasing said latch to render said spring means effective and means for limiting the relative movement of said casings, said inner

casing having an opening therein through which a letter may be inserted.

5. A letter box of the character set forth comprising a pair of telescoping casings, spring means urging said casings apart, latching means for holding said casings against relative movement, means for releasing said latching means whereby to render said spring means effective to move said casings apart, means for limiting the relative movement of said casings and a lock for locking said casings against relative movement.

10. A letter box of the class described comprising a pair of telescoping inner and outer casings, the inner casing having a portion of its front wall cut away whereby to permit access thereto when said casings are moved apart a predetermined distance, means for locking said casings in position to prevent access to the interior thereof, spring means arranged within said outer casing and urging said casings apart, a latch carried by said inner casing and cooperating with said outer 15 casing for rendering said spring means ineffective, means for releasing said latch whereby to permit the spring means to move the casings apart and means for limiting the relative movement of said casings.

15. In testimony whereof, I hereunto affix my signature.

JOSEPH ANDRASSY.
